(57) **CLAIM**

The ornamental design of an electrical module, as shown and described.

DESCRIPTION

FIG. 1 is a top, front, and right side perspective view of an electrical module showing our new design;

FIG. 2 is a bottom, front, and left side perspective view thereof;

FIG. 3 is a top plan view thereof;

FIG. 4 is a front elevation view thereof;

FIG. 5 is a bottom plan view thereof;

FIG. 6 is a rear elevation view thereof;

FIG. 7 is a left side elevation view thereof; and,

FIG. 8 is a right side elevation view thereof.

In the drawings, our design is showing in solid lines. Broken lines illustrate environment associated with the design being for illustrative purposes only and forming no part of the claimed design.
